(57) CLAIM

The ornamental design for a steering wheel with stick, as shown and described.

DESCRIPTION

FIG. 1 is a perspective view of a steering wheel with stick showing our new design according to one embodiment;

FIG. 2 is a right side elevational view, the left side elevational view being a mirror image thereof;

FIG. 3 is a front elevational view of the wheel portion of the steering wheel with stick taken along line 3—3 in FIG. 2;

FIG. 4 is a rear elevational view of the steering wheel with stick of FIG. 1;

FIG. 5 is a perspective view of a body portion of the steering wheel with stick of FIG. 1; and,

FIG. 6 is a perspective view of a steering wheel with stick showing a second embodiment of our new design, all other drawing views are substantially the same as in FIGS. 1—5.

The broken lines shown in the FIGS. 2 and 4 drawing views are for illustrative purposes only and form no part of the claimed design.
